US0D1067127S

(12) **United States Design Patent** (10) **Patent No.:** **US D1,067,127 S**
(45) **Date of Patent:** **** Mar. 18, 2025**

(54) **TRANSFER BOARD**

(71) Applicant: **Quanzhou Xingzhuo Outdoor Equipment Technology Co., Ltd., Quanzhou (CN)**

(72) Inventor: **Zhenxing Zhang, Quanzhou (CN)**

(73) Assignee: **Quanzhou Xingzhuo Outdoor Equipment Technology Co., Ltd., Quanzhou (CN)**

(**) Term: **15 Years**

(21) Appl. No.: **29/949,652**

(22) Filed: **Jun. 27, 2024**

(30) **Foreign Application Priority Data**

Apr. 28, 2024 (CN) 202430245852.1

(51) **LOC (15) Cl.** **12-12**

(52) **U.S. Cl.**

USPC **D12/128**

(57) **CLAIM**

The ornamental design for a transfer board, as shown and described.

DESCRIPTION

FIG. 1 is a front perspective view of a transfer board, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a transfer board shown in an alternate position of use.

The broken lines in the drawings illustrate the portions of the transfer board, which form no part of the claimed design.

1 Claim, 9 Drawing Sheets
